UNITED STATES PATENT OFFICE

DAVID FRANKLIN YOUNGBLOOD, OF SAN ANTONIO, TEXAS

JAIL

Application filed June 25, 1929. Serial No. 373,532.

This invention relates to jails of the type wherein the cell doors and the locks therefor are selectively operated from central points or operating stations and, among other objects, aims to provide an improved master control box and doors cooperating therewith so arranged as not to occupy any valuable space within the main cell room, the cells or the jailer's corridor.

10 In the accompanying drawings:—

Fig. 1 is a plan view of a typical jail room having a single row of cells and embodying the invention;

15 Fig. 2 is a fragmentary front elevation, on an enlarged scale, showing the control box and associated doors;

Fig. 3 is a section taken on the line 3—3 of Fig. 2;

20 Fig. 4 is a fragmentary section taken on the line 4—4 of Fig. 2;

Fig. 5 is a fragmentary section on an enlarged scale of the control box and its door;

Fig. 6 is a section taken on the line 6—6 of Fig. 5; and

25 Fig. 7 is a fragmentary section taken on the line 7—7 of Fig. 5.

In modern jails, it is customary to arrange the cells in one or more rows in the cell room leaving a prisoners' corridor and jailer's corridor. The master door and lock operating mechanism is usually arranged in a control box secured to a corridor wall and projecting into the jailer's corridor space. Operating levers usually have to be swung outside of the box farther into the jailer's corridor space, and also a hinged or swinging door has to be opened to afford authorized access to the mechanism. Such an arrangement makes it necessary to provide a relatively wide jailer's corridor to avoid obstructing the passageway. This involves increased floor space that is very expensive. This added expense is enormous in combined administration or court house and jail buildings where the jail rooms are located in the upper stories, because the size of the whole building must be increased.

This invention, therefore, aims to eliminate the obstruction in the jailer's corridor by the provision of an inset control box having

improved master operating means that never projects into the jailer's corridor, and also an improved arrangement of doors for the control box and the jailer's entrance to the prisoners' corridor, the main idea being to effect a great saving in the cost of the buildings.

Referring to Fig. 1, there is shown more or less diagrammatically, a typical plan of a jail room 10 or jail wing of a building, having only a single row of prisoners' cells 11. In this instance, the sliding cell doors 12 open into a prisoners' corridor 13 leading to an ante-chamber or safety vestibule 14 through a door 15; thence, to the jailer's and visitors' corridor 16. Also, a day room 17 is preferably located at this end of the row of cells so that one or more prisoners at a time may be admitted to it and there converse with counsellors or with visitors. Of course, it is to be understood that this invention may be advantageously employed in jails or prisons of widely different designs, this simple plan being selected merely for illustrative purposes.

Herein, the outside cage wall 18 between the jailer's corridor and the day room is made of tool-proof sheet metal or plates and the improved master control box 19, constituting this invention, is shown as being set in this wall in alinement with the row of cell doors. In some cases, however, the box may be set in front of the cells. This box is preferably substantially L-shaped to limit the space occupied by it inside the cells to the otherwise unused space under the cover box adjacent to the control box and to provide room in the front portion for an operating hand wheel 20 connected to a shaft 21 journaled within the casing and having a sprocket 22 adapted to drive the door and lock operating mechanism (not shown). The front end of the shaft is shown in Fig. 4 as passing through a partition in the casing which protects and conceals the operating mechanism.

As best shown in Figs. 4 and 5, the box is preferably made of sheet metal or tool-proof steel plates and the front is open. A special sliding door 23 is arranged to close the opening to prevent unauthorized access to the

operating mechanism. This door is preferably flush with the outside cage wall 18 and is adapted to slide to the right in a recess or inset portion 24 in the wall 18. It is preferably mounted on rollers which roll on a track 25 conveniently made of a structural angle (Fig. 6) and the upper edge of the door is protected and concealed by the vertical flange 26 of another structural angle. The lower edge of the door is shown as having structural angles 27 and 28 secured to its inner face and providing a recess 29 receiving a floor guide rail 30 also in the form of a structural angle. This floor rail is preferably cut away at intervals to permit the trash to be swept out of the floor of the box and recess.

At the right hand edge of the door, a flange 31 extending across the recess 24, is secured and to this flange an angle 32 is secured so that one of its flanges 33 will slide behind a flange 34 of an angle 35 within the box. It will be understood that the members 31 and 32 may be an ordinary structural channel.

To lock the sliding door there is shown a locking bar or plate 36 arranged within a housing 37 and extending the full height of the door and adapted to be projected therefrom so that it extends behind the angle 35. Herein, the housing 37 which consists of spaced flange members, has a plurality of diagonal parallel slots 38 receiving transverse pins 39 through the locking bar, the arrangement being such that, when the pins are seated in the bottoms of the slots, the bar is projected to lock the door, and as they are raised in the slots, the bar is retracted to unlock the door. Herein, an operating knob 40 is connected to a flanged disk member 41 which engages one of the pins 39. When the knob is turned to the left, as viewed in Fig. 5, the pin 39 is raised and thus lifts the locking bar and shifts it to unlocking position. Referring to Fig. 7, there is shown a pair of spaced projections or flanges 42 cooperating with a pin 39 and, on the opposite edge of the disk, is a notched flange 43 arranged to receive a locking member 44 projecting from the combination lock case 45. The latter lock is adapted to be operated by an ordinary combination knob 46, as shown in Fig. 5.

In some instances, it is desirable, though not essential, that the door for the control box shall cooperate with an adjacent vestibule door where such a door is used. Herein, the door for the control box cooperates with a similar sliding door 47 which guards the entrance to the corridors 14 from the jailer's and visitors' corridor 16. This door 47 is preferably also of panel construction, and has a glass window through which the jailer may observe any prisoner in the corridor. It is mounted to slide in the same manner as the door 23, the upper track 25 being extended across the corridor opening. The arrange-

ment is such that when both the door 47 and the door 23 are closed, they interlock with each other and with the walls, so that they cannot be pried open at either the sides or the ends.

Referring to Fig. 4, the panel door 47 is shown as having angles 48 secured to its rear side at the opposite edges, one flange of the angle 48 at the left-hand edge of the door being arranged to strike a corresponding flange 75 of an angle 49 on the inside of the plate or sheet metal partition 18. On the front face of the door is secured a strip 50 which extends beyond the left-hand edge so that the angle 48 and strip 50 straddle the edge of the wall 18, 80 or provide a pocket to receive the edge of the wall in that side of the door opening. A similar sheet metal strip 50 is also secured to the right-hand edge of the door and extends beyond the edge to overlap the left-hand edge 85 portion of the door 23 (Fig. 5).

To lock the entrance door and to prevent it from being pried open at the right-hand edge, there is shown an angle 51 secured to the rearwardly projecting flange of the angle 48 and this angle has a notched flange 52 arranged to slide behind a flange 53 of an angle secured to the left-hand side wall of the control box (Fig. 5). A spring latch 54 mounted in a suitable housing 55, is arranged to be projected into the notch in the flange 52. This latch is adapted to be operated from the inside of the control box and preferably has an operating handle 56 projecting through a longitudinal slot 57 in the casing 55. Of course, the construction of the latch member may be widely varied. The arrangement is such that the latch cannot be disengaged until the control box door 23 has been unlocked and opened. The arrangement is also such that the corridor door 47 cannot be opened until the control box door 23 is unlocked and opened. The flange 52, which extends behind the flange 53, prevents the door 47 from being pried outwardly. To prevent the left edge 110 of the door 23 from being pried inwardly, there is shown an angle 58 secured to the angle 51 and presenting a flange extending behind the edge of the door. This flange cooperates with the plate or strip 50 115 to provide a recess or channel for the left edge of the door. It will thus be seen that the flange members 51 and 52 on the door 47 cooperate with the door 23 to close the control box so that prisoners in the corridor 14 can- 120 not get access to the operating mechanism.

From the foregoing description, it will be observed that the jailer must first open the control box door before opening the corridor entrance door, both doors being locked by the combination lock. Instead of swinging the door open as has been the custom heretofore, it is slid open without taking up any space in the jailer's and visitors' corridor. When the jailer has selected and operated the desired 130

locks and doors of the cells 11, he may release the prisoners by opening the door 47. This door slides in front of and conceals or covers the lock operating mechanism, while the prisoners are being escorted through or into the jailer's and visitors' corridor, thus avoiding the danger of a prisoner jumping behind a swinging door. Neither does this door offer any obstruction to the passage of prisoners through the jailer's corridor. By arranging the control box and the doors in this manner, it is unnecessary to provide any extra width for the jailer's corridor on account of obstructions. All of the possible 10 obstructions to the free passage of persons or prisoners are eliminated.

Obviously, the present invention is not restricted to the particular embodiment thereof herein shown and described. Moreover, it is not indispensable that all of the features of the invention be used conjointly, since they may be employed advantageously in various combinations and sub-combinations.

What is claimed is:

1. In a cell room having a row of cells and cell doors arranged to be operated by a master locking and operating system, a partition at one end of the row of cells providing a corridor; a master control box providing a housing for said operating mechanism set inside of the partition in substantial alinement with the cell doors; and a sliding door for the control box substantially flush with the partition.

2. In a jail having a row of cells and cell doors adapted to be operated by a master controlling system; a partition at one end of the row of cells providing a corridor for the jailer; a master control box for said system inset within the partition in substantial alinement with the cell doors; a sliding door substantially flush with the corridor side of the partition wall; locking means for said door; and an inset portion in said partition providing a recess within which the door slides to open.

3. In a jail having cell doors arranged to be operated from a master control station, a partition providing a jailer's corridor; an inset control box in the partition; a sliding door for the control box; a sliding corridor door for the entrance leading to the cells arranged adjacent to the control box door, both of said doors being swung to roll on a common track and interlocking at their adjacent edges when closed; and a lock for the control box door preventing either door from being opened.

4. In a jail having cell doors arranged to be operated from a master control station, cage walls providing a jailer's corridor and a prisoners' corridor; an inset control box in one of the walls; a sliding door for the control box; a sliding corridor door providing an entrance to a vestibule leading to

the prisoners' corridor and arranged adjacent to the control box door; and a lock for the control box door preventing either door from being opened.

5. In a jail having cell doors arranged to be operated from a master control station, a partition providing a jailer's corridor; an inset control box in the partition; a sliding door for the control box; a sliding corridor door providing an entrance to a vestibule leading to the cells and arranged adjacent to the control box door; means on the corridor door interlocking with the adjacent edge of the control box door; and a combination lock for the control box door preventing unauthorized opening of either door.

6. In a jail having a plurality of cells arranged in a row, and a prisoners' corridor in front of the cells, a partition providing a jailer's corridor at one end of the row of cells and the prisoners' corridor; an inset master control box in said partition providing a housing for cell door operating mechanism; a sliding door for the control box; and a sliding door for the entrance to the prisoners' corridor adjacent to the control box, said corridor door presenting a channel at one edge to receive the adjacent edge of the control box door.

7. In a jail having a plurality of cells arranged in a row, and a prisoners' corridor in front of the cells, a partition providing a jailer's corridor at one end of the row of cells and the prisoners' corridor; an inset master control box in said partition providing a housing for cell door operating mechanism; a sliding door for the control box; and a sliding door for the entrance to the prisoners' corridor adjacent to the control box; a track suspending both of said doors; an interrupted door guide rail on the floor; and flange members on the doors providing a channel to guide the doors on said guide rail.

8. In a jail having a plurality of cells arranged in a row, and a prisoners' corridor in front of the cells, a partition providing a jailer's corridor at one end of the row of cells and the prisoners' corridor; an inset master control box in said partition providing a housing for cell door operating mechanism; a sliding door for the control box; and a sliding door for the entrance to the prisoners' corridor adjacent to the control box; a track suspending both of said doors; an interrupted door guide rail on the floor; flange members on the doors providing a channel to guide the doors on said guide rail; a flange member on one side edge of the control box door interlocking with the control box to prevent the door from being pried inwardly or outwardly at that edge; interlocking connections between the adjacent edges of the two doors when they are closed; means on the corridor door also interlocking with the control box to prevent the doors from be-

ing pried inwardly or outwardly at their adjacent side edges; interlocking connections between the corridor and its jamb; a flange member overlapping and concealing the upper edges of both of said doors; and a lock for said control box door to lock both doors.

9. In combination with a master control box for jail cell doors, a sliding door to afford access to the operating mechanism; a locking bar at one side of the door arranged to be projected into locking engagement with the control box; a combination lock cooperating with said locking bar; and means to prevent the door from being pried outwardly at any edge.

10. In combination with a master control box for jail cell doors, a sliding door to afford access to the operating mechanism; a flat locking bar arranged to be projected edge-wise into locking engagement with the control box and extending substantially the full height of the door adjacent to one edge; a housing on the door for the locking bar; slot and pin connections between the locking bar and housing; a handle connected to project and retract said bar; and a combination lock connected to lock the bar in projected position.

In testimony, that I claim the foregoing as my own, I have hereto affixed my signature.

DAVID FRANKLIN YOUNGBLOOD.
